GUSTAV EGLOFF AND HARRY P. BENNER, OF CHICAGO, ILLINOIS, ASSIGNEES TO UNIVERSAL OIL PRODUCTS COMPANY, OF CHICAGO, ILLINOIS, A CORPORATION OF SOUTH DAKOTA

APPARATUS FOR TREATING HYDROCARBONS

Application filed September 1, 1920, Serial No. 407,408. Renewed November 21, 1927.

This invention relates to an apparatus for treating hydro-carbons, and this present application refers more particularly to an apparatus adapted for the cracking of petroleum oil into gasolene, gasolene-like bodies or other light hydro-carbons.

The salient feature of the invention consists in conducting said cracking operation so that the vapors are subjected to horizontal 10 dephlegmating action in a continuous system of the coil type.

In the drawings, Fig. 1 shows a side elevation parts broken away and shown in section of our apparatus. Fig. 2 is a sectional view 15 showing one of the upper baffle members employed in the dephlegmator, and Fig. 3 is a sectional view showing one of the lower baffle members.

Referring to the drawings, 1 designates the 20 furnace, having burner 2, the bridge wall 3, stack 4. In this furnace is mounted heating coil 5, as for example a coil composed of tubes four inches internal diameter. The heated oil, while still in liquid phase, passes out 25 through valve 6 into the side of an expansion chamber 7. This expansion chamber is provided with residue draw off 8, controlled by valve 9 and vapor outlet 10, controlled by valve 11. The vapor outlet 10 is connected 30 to a dephlegmator 12. This dephlegmator 12 is provided with an inclined bottom portion 13, the lowermost part of which is connected to pipe 14, leading back to the charging line 15. A valve 16 is interposed in this 35 charging return line 14. The dephlegmator member 12 is provided with alternately disposed baffles 17 and 18, the latter being perforated or apertured, as shown at 19, to permit the reflux condensate to flow down the 40 pipe 14. The uncondensed vapors pass out of the dephlegmator through line 20, controlled by valve 21, to a condenser coil 22, which condenser coil is seated in water condenser box 23; the coil 22 in turn connects to 45 the receiver 24, which receiver 24 is provided with liquid draw off pipe 25, having throttle valve 26 and gas outlet pipe 27, having throttle valve 28. Fresh charging stock is supplied to the heating coil 5 by means of pump 29, leading to any suitable source of supply.

The following illustrative run of a process carried out in the apparatus may be given: Oklahoma gas oil of say 33 deg. Baumé gravity, is continuously fed to the heating coil 5, where it is heated to a temperature 55 at the discharge end of say 830 deg. F., care being taken to prevent the temperature from getting so high as to cause vapors in the coil. In other words, the oil is maintained at that temperature under the pressure used 60 which will keep it in the liquid phase. A pressure of 100 pounds may be maintained throughout the system clear through to the receiver if desired, or a differential pressure 65 may be maintained on the system, as for example 150 pounds on the heating coil 5, 100 pounds on the expansion chamber, 75 pounds in the dephlegmator, 50 pounds or atmospheric pressure on the condenser coil and receiver. A still further differential pressure 70 may be obtained by placing a valve 30 between the outlet of the condenser coil and the upper end of the receiver. In this way a pressure of say 500 pounds might be maintained on the heating coil 5, 400 pounds in 75 the expansion chamber, 300 pounds on the dephlegmator, 200 pounds on the condenser coil and 100 pounds on the receiver. Where a differential pressure is maintained, the reflux condensate from the dephlegmator may 80 be drawn off to any suitable receiver through a line 31 provided with valve 32, in which case valve 16 will be closed. Or even where a differential pressure is used and it is desirable to return the reflux condensate directly to the heating coil 5, a pump 33 may be interposed in the line 16, in which case bypass lines 34 and 35, having valves 36 and 37, may 85 be used, and in such case, valve 38 is interposed in the manner shown in the drawing. The arrangement is such that the pump may or may not be used, but if the dephlegmator is maintained at a lower pressure than the heating coil, then the reflux condensate must be pumped back to the heating coil or else 90 conveyed to a separate receptacle.

We claim as our invention:

An apparatus of the character described, comprising a furnace, a coil therein, means for feeding oil to the coil, an expansion cham- 100

ber disposed exteriorly of the furnace and in communication with the coil, a horizontally disposed dephlegmator communicating with said expansion chamber, a vapor discharge from the dephlegmator, and means for returning reflux condensate from said dephlegmator to the heating coil, said dephlegmator having an inclined wall and provided with a plurality of baffles, the reflux discharge being near one end of the dephlegmator.

GUSTAV EGLOFF.
HARRY P. BENNER.
